Des. 211,740

Patented July 23, 1968

211,740

FINGER WHEEL TELEPHONE DIAL

David W. Hagelbarger, Morris Township, Morris County, N.J., assignor to Bell Telephone Laboratories Incorporated, Berkeley Heights, N.J., a corporation of New York

Continuation-in-part of design application 87,878, Oct. 23, 1965. This application July 19, 1967, Ser. No. 7,874

Term of patent 14 years

(Cl. D26—14)

FIG. 1

FIG. 2

FIG. 3

FIG. 1 is a perspective view of a finger wheel telephone dial showing my new design;

FIG. 2 is a front elevation view; and

FIG. 3 is a side elevation view thereof.

The broken lines are shown for illustrative purposes only.

This application is a continuation-in-part of my application Ser. No. D.87,878, filed Oct. 23, 1965 and now abandoned.

I claim:

The ornamental design for a finger wheel telephone dial, as shown and described.
